UNITED STATES PATENT OFFICE.

ALBERT M. HUGHES, OF PASADENA, CALIFORNIA.

FLANGE-PIN REMOVER.

Application filed August 19, 1926. Serial No. 130,257.

The invention relates to improvements in tools for use by piano repair men when removing flange pins and substituting others.

One object of the invention is to provide an exceptionally simple and inexpensive, yet an efficient and reliable tool which embodies an easily operated punch for removing the flange pins.

A further object is to make novel provision whereby a part of the mounting and operating means for the pin removing punch, assists in properly holding an anvil plate upon a base block.

Another object of the invention is to provide the base block with a plurality of cells to contain flange pins of different sizes, and to equip said base with a slidable cover for the cells, said cover having a frictional connection with the base so that it may be set with its inner end disposed at any selected cell from which pins are to be removed. Thus, after once locating the proper size pins to be used, it is an easy matter to locate the proper cell whenever a pin is to be withdrawn therefrom.

With the foregoing in view, the invention resides in the novel subject matter herein-after described and claimed, the description being supplemented by the accompanying drawings.

Fig. 1 is a perspective view of a tool constructed in accordance with my invention, showing it as used for removing a flange pin from a portion of a piano action;

Fig. 2 is a central vertical longitudinal section, partly in elevation; and

Fig. 3 is a transverse sectional view on line 3—3 of Fig. 2.

In the drawings above briefly described which illustrate the preferred form of construction, the numeral 4 designates a horizontally elongated, rectangular, base block which may be formed of wood or metal, as desired. Near its upper surface, the opposed sides of this block 4 are formed with longitudinal guide grooves 5 for a purpose to appear, and near one of its ends, said block is formed with a pin-receiving socket 6 and with a post-receiving socket 7, both of which open through the upper face of the block. The remainder of the length of the block 4 is occupied by cells 8 which open through its upper side and are intended to contain flange pins of different sizes, and if desired, the sizes of the pins may be stamped

or otherwise provided on the block, adjacent the cells.

An elongated cover plate 9 is provided for the cells 8, said plate having angular side flanges 10 slidably and frictionally received in the grooves 5 and being provided also with a suitable handle 11. After first determining the proper size of the pins to be used on any repair job, the cover plate 9 may be set so that its inner end is disposed adjacent the cell 8, containing pins of that size. Thus, the repair man knows that each time a pin is to be removed from a cell, it should be taken from the particular cell at the inner end of the cover plate 9. Thus, it is practically insured that all of the pins which he removes for use, shall be of the proper size.

An anvil plate 12 rests upon the end portion of the base block 4, which is provided with the sockets 6 and 7, and said plate is provided with openings 13 and 14 aligned with these sockets respectively. The side edges of the plate 12 are provided with angular flanges 15 which engage the grooves 5 so as to hold the plate against upward movement with respect to the base block 4. Longitudinal movement of this anvil plate upon the base block, is prevented by a vertical post 16 which passes through the opening 14 and is threaded or otherwise secured in the socket 7. When the post is removed however, one anvil plate may be slid from the base block 4 and another anvil plate substituted, should this be advisable, for instance due to accidental injury to the plate previously in use.

A lever 17, having any desired handle such as that indicated at 18, is fulcrumed at 19 to the upper end of the post 16, and a punch 20 is pivoted at 21 to said lever 17, the lower end of said punch terminating in a pin-like portion 22 which is aligned with the socket 6 and the opening 13, so that it may be used to force a flange pin from a portion A of a piano action, as will be clear from Figures 1 and 2, the pin being forced into the socket 6, as it is depressed out of the position which it previously occupied.

When fitting new pins in place, it is often necessary that they be cut to the proper length. For this purpose, I have shown fixed and movable cutters 23 and 24 carried by the post 16 and the lever 17 respectively.

In addition to the advantages above

pointed out, attention may be invited to the fact that when the cover plate 9 is closed, it abuts and is flush with the upper side of the anvil plate 12. Thus, the two plates form a single smooth surface upon which to rest the portion of the action, from which the flange pin is to be removed. In addition to this, the plate 9 normally closes the flange pin cells, but gives access to them whenever desired.

On account of the advantages existing from the details disclosed, they are preferably followed. However, within the scope of the invention as claimed, variations may be made.

I claim:—

1. A flange pin remover comprising a base block having a post-receiving socket and a pin-receiving socket both of which open through its upper surface, the opposed vertical sides of said block being formed with longitudinal guides, an anvil plate resting on said block and having down-turned flanges engaged with said guides, said plate being formed with a pin-receiving opening and a post-receiving opening alined with the corresponding sockets of the block, and punch-carrying and operating means includ-

ing a post fitting into said post-receiving opening and socket and holding said anvil plate against sliding upon the block.

2. A device of the class described comprising a horizontally elongated base block having a plurality of cells spaced apart along its length and opening through its upper face, said cells being intended to contain flange pins of different sizes, and a cover plate for said cells having a frictional sliding connection with said base block, said cover plate being slideable longitudinally of said block, whereby its inner end may be set at any selected cell from which pins are to be used.

3. A device of the class described comprising an elongated base recessed to receive flange pins, pin-removing means operatively connected with said base and movable downwardly toward the same, and a metal cover for said base formed of sections whose upper sides are flush to support the work, one of said sections being a cover for the recessed portion of the base and being movably mounted to give access to the contained flange pins.

In testimony whereof I have hereunto affixed my signature.

ALBERT M. HUGHES.
